United States Patent Office

Des. 183,481
Patented Sept. 9, 1958

183,481

COMBINED BENCH AND KNEELING RAIL

Robert B. Feistel, Jr., Oklahoma City, Okla., assignor
to W. H. Stewart Co., Oklahoma City, Okla., a corpo-
ration of Oklahoma

Application November 20, 1957, Serial No. 48,566

Term of patent 14 years

(Cl. D15—8)

Fig. 1 is a front perspective view of a combined bench and kneeling rail showing my new design;

Fig. 2 is a rear perspective view;

Fig. 3 is a side elevation;

Fig. 4 is a face view; and

Fig. 5 is a top plan view.

I claim:

The ornamental design for a combined bench and kneeling rail, substantially as shown.
